FIRE CONTROL MECHANISM FOR AUTO-
MATIC AND SEMIAUTOMATIC FIRE-
ARMSHarry H. Sefried, II, New Haven, Conn., assignor
to Olin Industries, Inc., New Haven, Conn., a
corporation of Delaware

Application January 2, 1948, Serial No. 54

12 Claims. (Cl. 89—140)

1

The present invention relates to improvements in self-loading firearms and relates more particularly to self-loading firearms of the type which may be manually set to operate either as a full automatic firearm or a semiautomatic firearm. In other words, the firearm of the present invention may be selectively set to automatically reload and repeatedly discharge as long as the trigger is held in a retarded or pulled position, or to automatically load but require the operation of the trigger for each shot.

One of the objects of the present invention is to provide a superior fire-control mechanism whereby a firearm will function selectively either automatically or semiautomatically at the option of the user, and which possesses a high degree of reliability despite long use under adverse conditions.

Another object of the present invention is to provide a superior automatic and semiautomatic firearm having a superior fire-control mechanism of such character as will not only permit the selection of automatic or semiautomatic fire, but which will, in both instances, insure that the firing cannot be accomplished until such time as the breech-bolt is fully closed and adequately locked.

A further object of the present invention is to provide a superior fire-control mechanism which may be incorporated in a firearm of the well-known Garand military type without requiring the extensive re-design thereof.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

Fig. 1a is a broken view of the central portion of an automatic and semiautomatic firearm embodying the present invention, shown mainly in side elevation with the stock partly broken away and in vertical section, the breech-bolt being shown in its fully closed position with the selector-member and associated parts positioned in readiness to cause the firearm to operate semiautomatically;

Fig. 1b is a broken view of the portion of the firearm immediately forwardly of the parts shown in Fig. 1a, with the stock shown partly in section and with the tubular front portion of the bolt-operating slide also in section;

Fig. 2 is a view similar to Fig. 1a, except that

2

the parts are shown in the positions which they assume at the instant of firing;

Fig. 3 is a view similar to Figs. 1a and 2, but showing the selector-member shifted to enable the firearm to function as a full automatic firearm and with the trigger being shown in its "pulled" position and the hammer being shown as held in a cocked position by the tertiary sear, and the breech-bolt and associated parts being shown in the positions which they assume during the forward movement of the breech-bolt and just prior to the latter reaching its breech-closing position;

Fig. 4 is a view similar to Fig. 3, but with the breech-bolt shown in its breech-closing position and locked therein and with the tertiary sear-bar in the position it assumes substantially at the instant of releasing the hammer;

Fig. 5 is a broken transverse sectional view taken on the line 5—5 of Fig. 1a;

Fig. 6 is a transverse sectional view taken on the line 6—6 of Fig. 3, but leaving the receiver in elevation;

Fig. 7 is a broken sectional view taken on the line 7—7 of Fig. 3, but leaving the receiver in elevation;

Fig. 8 is a perspective view of the hammer detached;

Fig. 9 is a perspective view of the unit comprising the combined trigger and primary sear-arm and the secondary sear;

Fig. 10 is a perspective view of the tertiary sear detached;

Fig. 11 is a perspective view of the unit comprising selector-lever, sear-holding member and pivot-pin shown as assembled; and

Fig. 12 is a broken perspective view looking mainly toward the inner face of the rear portion of the bolt-operating slide.

The main features of the firearm illustrated in the accompanying drawings are of the well known "Garand" type and comprising a receiver generally designated by the reference character 10, a barrel 11, a trigger-plate generally designated by the reference character 12 and a stock 13. The barrel 11 projects rigidly forwardly from the forward end of the receiver 10, while the trigger-plate unit 12 is located generally below the receiver 10 in a manner usual in military firearms. The parts 10, 11 and 12 are suitably secured to the stock 13.

At its lower-rear portion, the trigger-plate unit 12 is formed with a loop-like trigger-guard 14 accommodating and shielding the finger-piece 15 of a trigger generally designated by the refer-

ence character 16. The said trigger 16 is mounted for pivotal movement upon a trigger-pin 17 extending transversely of the firearm structure and supported at its respective opposite ends in the two spaced-apart side-plates 18 and 19 forming integral features of the trigger-plate unit 12, as may be seen by reference to Figs. 6 and 7 in particular.

The trigger 16 projects upwardly substantially above the trigger-pin 17 to provide a primary sear-arm 20. The said sear-arm 20 is provided at its upper-forward portion with a transverse cocking-lug 21 having an underface shaped to provide what may be aptly termed a "primary" cocking-abutment 22. The said primary cocking-abutment 22 is adapted to be releasably engaged (Fig. 1a) with a complementary primary cocking-abutment 23 formed at the forward-lower corner of a bifurcated cocking-arm 24 constituting an integral extension of a firing-member in the form of a pivotal-hammer 25. The cocking-arm 24, just referred to, is bifurcated as just described to provide clearance for the upper portion of the primary sear-arm 20 when the hammer is in its cocked position.

The hammer 25 above referred to is mounted for swinging movement about a transversely-extending hammer-pin 26 supported in the trigger-plate unit 12 and is urged to swing in a clockwise direction by a helical hammer-spring 27. The said hammer-spring partly envelops and thrusts forwardly upon a plunger 28 which latter has its forward end engaged with the said hammer. The hammer-spring 27 is mainly housed within and thrusts rearwardly upon a spring-housing 29 having its rear end loosely supported upon the trigger-pin 17.

The hammer 25 when released to the action of the hammer-spring 27 is adapted to strike the rear end of a firing-plunger 30 and drive the same forwardly to discharge a cartridge in a manner well known in the art. The said firing-plunger extends centrally through a breech-bolt 31, which latter will be more fully hereinafter described.

In addition to its primary cocking-abutment 23, the cocking-arm 24 of the hammer 25 is formed at its lower-rear portion with a secondary cocking-abutment 32 which slopes upwardly and forwardly (when the hammer 25 is cocked) and which extends transversely also along the lower-rear corner of a cocking-lug 33 offsetting laterally toward the right side of the firearm from the lower-rear portion of the cocking-arm 24, as is especially well shown in Fig. 8. The upper surface of the cocking-lug 23 just referred to provides a third or tertiary cocking-abutment 34 for purposes as will hereinafter appear.

As thus constructed, the hammer 25 or equivalent firing-member is provided with three cocking-abutments, i. e., the primary cocking-abutment 23, the secondary cocking-abutment 32 and the tertiary cocking-abutment 34.

The secondary cocking-abutment 32 of the hammer 25 is adapted to be releasably engaged by a secondary cocking-abutment 35 forming a feature of a secondary sear generally designated by the reference character 36. The forward portion of the said secondary sear is bifurcated so as to fit over the primary sear-arm 20 of the trigger 16, as is indicated in Fig. 9. The bifurcated forward portion of the secondary sear 36 is pivotally mounted upon the sear-arm 20 by means of a transverse sear-pin 37. The forward lower corner of the secondary sear 36 is pref-

erably rounded as is shown, to provide a thrust-nose 38 extending forwardly of the front face of the sear-arm 20 into position to be engaged by a thrust-surface 39 at the rear of the spring-housing 29. The thrust-nose 38 is located in such position with respect to the sear-pin 37 as to cause the rearward thrust of the spring-housing 29 to exert a yielding effort to turn the secondary sear in a clockwise direction with respect to the sear-arm 20 by which it is carried. Thus, the hammer-spring 27 not only urges the said secondary sear to turn about the sear-pin 37 in a clockwise direction but it simultaneously urges the entire trigger 16 to turn in a counterclockwise direction in opposition to the "pull" applied to the finger-piece 15.

At its rear, the secondary sear 36 is formed with an upwardly-and-rearwardly-curving sear holding-finger 40 which is adapted to have its forward face engaged by the rear face of a sear-holding finger 41 forwardly-and-downwardly-curving from the upper portion of a sear-holding member 42.

On its right side, the sear-holding member 42 is formed with an upwardly-facing ledge 43 against which is seated the lower end of a selector-lever 44 which may be conveniently formed of sheet metal and which is formed at its upper end with a finger-piece 45 extending into a position for manipulation from the exterior of the firearm structure. Extending transversely through the lower portion of the selector-lever 44 and the sear-holding member 42 is a pivot-pin 46 supported (Fig. 7) at its respective opposite ends in the side plates 18 and 19 of the trigger-plate unit 12. The pivot-pin 46 in addition to providing for the pivotal movement of the unit comprising the sear-holding member 42 and the selector-lever 44, also serves to hold the lower end of the said selector-lever seated against the ledge 43 on the member 42 to thus rigidly couple the said parts together for concurrent swinging movement.

In its lower portion, the sear-holding member 42 is provided with a transverse bore 47 in which is mounted on a helical detent-spring 48 and the respective inner portions of two similar detent-plungers 49-49, as is shown in Fig. 7. The said detent-plungers are urged outwardly in opposite directions respectively by the detent-spring 48 and into suitable detent-pockets 50 and 51 according to the particular position into which the sear-holding member 42 is swung. The said detent-plungers 49-49 thus serve to yieldingly hold the unit comprising the sear-holding member 42 and the selector-lever 44 in either of two positions for purposes as will hereinafter appear.

At its lower end the sear-holding member 42 is provided with a downwardly-extending guard-lug 52 which is adapted to coat, in the manner as will hereinafter appear, with an upwardly-extending guard-lug 53 formed upon the trigger 16.

Coacting with the tertiary cocking-abutment 34 of the hammer 25 is a downwardly-facing tertiary cocking-abutment 54 formed at the rear of a sear-arm 55 constituting a feature of a tertiary sear, generally designated by the reference character 56.

The tertiary sear 56 may be conveniently formed of heavy-gauge sheet metal and is generally of bar-like form adapted for reciprocation lengthwise of the receiver 10 adjacent the right side thereof. The downwardly-extending sear-arm 55 is integrally connected to the main portion of the tertiary sear by a reach 57 extending trans-

versely of the firearm structure so as to locate the sear-arm 55 in position to enable the tertiary cocking-abutment 54 to engage with the tertiary cocking-abutment 34 of the hammer 25.

Adjacent its forward end, the tertiary sear 56 is provided with a rearwardly-facing tripping-abutment 58 and with an inwardly-extending guide-pin 59, which latter rides in a slot 60 formed in the depending side-wall portion 61 of the receiver 10. The said depending side-wall portion is located forwardly of the trigger-plate unit, hammer and associated features and provides for the accommodation and support of a suitable box-magazine indicated at 62.

The tertiary sear 56 has its forward end supported for limited reciprocation lengthwise of the firearm structure by means of the guide-pin 59 and the slot 60. The rear portion of the said sear 56 is supported against downward displacement by having the lower edge of its sear-arm 55 slidably engaging with the upper surface of the right-hand side-plate 19 of the trigger-plate unit 12.

For the purpose of yieldingly urging the tertiary sear 56 rearwardly into position to engage its tertiary cocking-abutment 54 with the tertiary cocking-abutment 34 of the hammer 25, a helical sear-spring 63 is employed. The said sear-spring encircles a headed plunger 64 slidable in a guide-opening 65 formed in the reach 57 of the sear 56. The sear-spring 63 has its rear end seated against the front face of the reach 57 and has its forward end seated against the head of the plunger 64 so as to force the forward end of the said plunger in a suitable recess formed in the rear edge of the side-wall portion 61 of the receiver 10.

The tripping-abutment 58 of the tertiary sear 56 is adapted to be engaged by a rearwardly-facing tripping-abutment 66 located adjacent the rear end and constituting a feature of a bolt-operating slide or member 67 mounted for reciprocation lengthwise of the firearm structure on the right side thereof. The said bolt-operating slide corresponds, in the main, to the member in the well-known Garand rifle and is commonly referred to in the nomenclature thereof as the "transmitting-bar."

The breech-bolt 31 before referred to corresponds generally to the breech-bolt of the well-known Garand rifle and is provided on its right side with a locking-lug 68 adapted to oscillate into and out of engagement with a forwardly-facing locking-abutment 69 forming the rear wall of a clearance-notch 70 formed in the adjacent side-wall of the receiver 10 in a manner well understood in the art.

Extending outwardly from the forward portion of the locking-lug 68 of the breech-bolt 31 is an integral actuating-lug 71 extending into a recess 72 in the inner face of the rear portion of the bolt-operating slide 67.

The bolt-operating slide 67 is formed at its rear end with a laterally-projecting finger-piece 73 by means of which the firearm may be manually operated.

In a manner well understood in the art, the cam-recess 72 in the bolt-operating slide 67 and the actuating-lug 71 of the breech-bolt 31 are shaped to cooperate in such manner that when the said bolt-operating slide is moved rearwardly from its normal forward position, the breech-bolt 31 will be first turned so as to disengage the locking-lug 68 thereof from the locking-abutment 69 of the receiver 10, whereupon the said breech-bolt will be moved directly rearwardly. The rear-

ward movement of the breech-bolt, in a manner usual in firearms, will effect the extraction and ejection of the just-fired cartridge and the cocking of the hammer 25, which latter the said breech-bolt overrides.

Upon its forward stroke, the bolt-operated slide 67 will first draw the breech-bolt 31 forwardly until the rear face of the locking-lug 68 of the said breech-bolt is in registration with the locking-abutment 69, whereupon the said breech-bolt will be turned to again lock the breech-bolt in its forward or breech-closing position—all in the manner common in firearms.

Force may be applied to effect the rearward movement of the bolt-operating slide 67 and, hence, also of the breech-bolt 31, in any suitable manner. In the instance shown, the actuating-means for the said bolt-operating slide is the same as that employed in the Garand rifle and includes a tubular piston 74 rigid with the forward end of the said slide and located beneath the barrel 11. The said tubular piston 74 houses a helical breech-closing spring 75 which, in the usual manner, exerts a constant-but-yielding effort to hold the bolt-operating slide 67 in its foremost position and, hence, serves to hold the breech-bolt 31 in its forward breech-closed and locked position.

The upper edge of the tertiary sear 56 rides in a downwardly-opening groove 76 formed in the right side wall 61 of the receiver 10.

Semiautomatic operation

Let it be assumed for purposes of description that it is desired to have the firearm above described function as a semiautomatic firearm, i. e., automatically extract and eject just-fired cartridges and reload but requiring the individual pulling of the trigger for each desired shot.

Under the circumstances above referred to, the selector-lever will be moved into the position in which it is shown in Figs. 1a and 2, together with the seam-holding member 42 coupled thereto.

With the selector-lever set as above described, it may be assumed for purposes of description and as is shown in Fig. 1a that the hammer 25 is cocked and the trigger 16 is released from rearward finger pressure.

In Fig. 1a, the hammer 25 is shown as being held in its cocked position by the primary cocking-abutment 22 of the primary sear-arm 20 of the trigger 16, while both the secondary sear 36 and the tertiary sear 56 are in their retired positions.

Now when the trigger is pulled into the position in which it is indicated in Fig. 2, the primary cocking-abutment 22 will be retired and the hammer 25 will be released to the action of the hammer-spring 27 and will swing upwardly into the position in which it is shown in Fig. 2, to thereby strike the firing-plunger 30 and thus effect the discharge of the firearm.

Substantially instantaneously with the above action, energy from the just-fired cartridge will kick the bolt-operating slide 67 rearwardly in a manner well known in the art and as exemplified, for instance, in the well-known Garand military firearm.

The rearward movement of the bolt-operating slide 67 as just above referred to, will by virtue of the coaction between its cam-recess 72 and the actuating-lug 71 of the breech-bolt 31, first cause the said breech-bolt to be oscillated laterally to unlock the same, as previously described, and to subsequently move the said

breech-bolt rearwardly to effect the extraction and ejection of the just-fired cartridge in a manner common in automatic and semiautomatic firearms.

As the breech-bolt 31 is moved rearwardly as above described, the hammer 25 will be swung in a counterclockwise direction by the overriding action of the rear portion of the breech-bolt 31, and should the trigger 16 still be held "pulled" during such movement (which is normal), the said hammer will be caught and temporarily held in a cocked position by the engagement of its secondary cocking-abutment 32 with the secondary cocking-abutment 35 of the secondary sear 36, which latter will at this time be in its advanced position, as is shown in Fig. 2. As soon, however, as the trigger is released, the hammer will be released by the said secondary sear and will be caught by the primary cocking-abutment 22 of the trigger so that the parts just referred to will again assume the positions in which they are shown in Fig. 1a.

After completing its rearward travel, the breech-bolt 31 will be drawn forwardly by the return movement of the bolt-operating slide 67 which latter will act under the urge of the breech-closing spring 75 (Fig. 1b).

During its forward travel, the breech-bolt 31 will pick up a fresh cartridge in the manner usual in self-loading firearms and will insert such fresh cartridge into the cartridge-chamber of the firearm. When in the forward travel of the breech-bolt 31, its locking-lug 68 is brought into registry with the locking-abutment 69 of the receiver 10, the breech-bolt will be turned laterally and restored to the fully-locked position indicated in Figs. 1a and 2.

The final forward movement of the bolt-operating slide 67 (following the closing and locking of the breech-bolt) will engage its tripping-abutment 66 with the tripping-abutment 58 and then shift the tertiary sear 56 forwardly against the tension of the sear-spring 63. This action will shift the tertiary cocking-abutment 54 of the said tertiary sear forwardly out of the path of movement of the tertiary cocking-abutment 34 of the hammer 25.

The mechanism will now be in the position indicated in Fig. 1a, preparatory to another discharge of the firearm and the subsequent automatic reloading thereof as soon as the finger-piece 15 of the trigger 16 is pulled rearwardly.

It will be noted by reference to Figs. 1a and 2 that when the selector-lever 44 and its unitary sear-holding member 42 are in the positions in which they are shown in the said figures, the guard-lug 52 of the member 42 is located forwardly and in a clearance position with respect to the complementary guard-lug 53 of the trigger 16. Hence, as the trigger is pulled, the guard-lug 53 will ride upwardly to the rear of the guard-lug 52 without interference. The construction and arrangement, however, is such that the coaction of the guard-lugs 52 and 53 will prevent the selector-lever 44 from being shifted until such time as the trigger is released.

Fully-automatic operation

Let it now be assumed that it is desired to have the firearm function as a fully-automatic weapon, i. e., effect the continuous discharge of cartridges as long as the trigger is held in its pulled position.

To accomplish the purpose above referred to, 75

the selector-lever 44 and its unitary sear-holding member 42 may be manually shifted from the positions in which they are shown in Figs. 1 and 2 into the positions in which they are shown in Figs. 3 and 4.

The movement of the sear-holding member 42 above described will cause its downwardly-extending sear-holding finger 41 to hook itself in front of the complementary sear-holding finger 40 of the secondary sear 36, to thus restrain the secondary cocking-abutment 35 of the latter from swinging forwardly into an active position when the primary sear-arm 20 of the trigger 16 is moved forwardly by rearward draft upon the finger-piece 15, all in a manner as will hereinafter appear.

In Fig. 3, the trigger 16 is shown as pulled and the breech-bolt is shown as approaching its breech-closing position following a previous discharge of the firearm. With the trigger pulled as just above described, it will be noted by reference to Fig. 3 that the coaction of the two sear-holding fingers 40 and 41 serves to maintain the secondary cocking-abutment 35 of the secondary sear 36 out of the path of movement of the secondary cocking-abutment 32 of the hammer 25, so that, in effect the said secondary sear is rendered inoperative.

Since at this time the trigger 16 is pulled, its primary cocking-abutment 22 will also be retired out of the path of movement of the primary cocking-abutment 23 of the hammer 25. Thus, under the present conditions, both the primary cocking-abutment 22 and the secondary cocking-abutment 35 are retired, thus leaving the cocking of the hammer 25 or its equivalent entirely dependent upon the engagement of the tertiary cocking-abutment 54 of the tertiary sear 56 with the tertiary cocking-abutment 34 of the hammer, as is indicated in Fig. 3.

After the forward movement of the bolt-operating slide 67 (under the urge of the breech-closing spring 75) has effected the locking of the breech-bolt 31 in its breech-closing position, the continued forward movement of the said bolt-operating slide will engage its tripping-abutment 66 with the tripping-abutment 58 of the tertiary sear 56. The action last referred to will cause the tertiary sear to be moved forwardly against the counter-urge of its sear-spring 63, to thereby remove the tertiary cocking-abutment 54 of the said sear out of the path of movement of the tertiary cocking-abutment 34 of the hammer 25, to thus release the hammer and permit the discharge of the firearm. In Fig. 4, the tertiary sear 56 is shown as moved forwardly in the manner just above described to an extent necessary to bring its tertiary cocking-abutment 56 substantially into the position which it would assume at the instant of the disengagement of the latter from the tertiary cocking-abutment 34 of the hammer.

As long as the trigger 16 is held pulled and as long as the ammunition lasts, the firearm will continue to repeatedly discharge. Each time that the firearm is discharged under the conditions just being described (fully automatic), the bolt-operating slide 67 and breech-bolt will be moved rearwardly, thereby releasing the tertiary sear 56 to the action of the sear-spring 63 so as to again interpose the tertiary cocking-abutment 54 of the said sear in the path of movement of the tertiary cocking-abutment 34 of the hammer 25. Thus, the hammer 25 will be held in its cocked position by the tertiary sear 56 until after the breech-bolt 31 has been fully closed and locked, whereupon

the tertiary sear will be moved forwardly to again effect the discharge of the firearm.

It is to be noted that when the selector-lever 44 is in the position in which it is shown in Figs. 3 and 4, it will be prevented from being moved back into the position in which it is shown in Figs. 1a and 2 by the fact that the guard-lug 53 of the trigger 16 will be interposed in the path of movement of the guard-lug 52 of the sear-holding member 42 as long as the trigger is held in its pulled position.

Résumé

From the foregoing description and by reference to the accompanying drawings, it will be seen that the construction and arrangement of parts is such that the selector-lever 44 or its equivalent is effectively prevented from being shifted as long as the trigger 16 is held pulled.

It will be further apparent that when the firearm is set to function as a semiautomatic firearm, both the secondary cocking-abutment 35 and the primary cocking-abutment 22 are brought into play to sequentially releasably hold the hammer in its cocked position. Meanwhile, however, and in each instance, the tertiary cocking-abutment 54 will be in a guard position to prevent the accidental discharge of the firearm until such time as the breech-bolt 31 is fully in its breech-closing position and locked therein.

It will also be apparent from the foregoing and by reference to the accompanying drawings that when the selector-lever 44 is shifted to cause the firearm to function as a fully-automatic firearm, the secondary sear 36 is rendered inoperative and as long as the trigger 16 is held pulled (as would normally be the case to effect full automatic fire), the entire task of holding the hammer 25 in its cocked position devolves upon the tertiary sear 56. It is to be understood, however, that at any time during the full automatic operation of the firearm it is desired to "cease fire," the release of rearward draft upon the finger-piece 15 of the trigger 16 will restore the primary cocking-abutment 22 of the primary sear-arm 20 into position where it will releasably hold the hammer 25 in a cocked position by engagement with the primary cocking-abutment 23 of the said hammer.

By the unique combination and arrangement of parts above described, a self-loading firearm may be selectively caused to function either as a semiautomatic or fully-automatic firearm in a manner which is simple, reliable and effective, despite rough handling and long periods of use.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. An automatic and semiautomatic firearm, including in combination: a receiver; a unit comprising a breech-bolt movable in the said receiver and a bolt-operating member mounted for movement adjacent the said receiver and operatively connected to the said breech-bolt for moving the same; a spring-pressed firing-member provided with a primary cocking-abutment, a secondary cocking-abutment and a tertiary cocking-abutment; a trigger; a primary sear operatively associated with the said trigger for being moved

thereby and having a primary cocking-abutment releasably engageable with the primary cocking-abutment of the said firing-member when the said trigger is released; a secondary sear having a secondary cocking-abutment normally releasably engageable with the secondary cocking-abutment of the said firing-member when the said trigger is pulled and movable with respect to the said trigger for being held in a retired position; a tertiary sear having a tertiary cocking-abutment releasably engageable with the tertiary cocking-abutment of the said firing-member; manually-operable control-means engageable with the said secondary sear for releasably holding the same in a retired position; means operatively connecting the said secondary sear to the said trigger to effect the movement of the former by the latter, the said means including a spring yieldingly urging the secondary cocking-abutment of the said secondary sear into position for releasable engagement with the secondary cocking-abutment of the said firing-member and permitting the relative movement of the secondary sear in the opposite direction; and means actuated by the said unit to retire the said tertiary sear as the said breech-bolt moves into its breech-closing position.

2. An automatic and semiautomatic firearm, including in combination: a receiver; a breech-bolt movable in the said receiver; a bolt-operating member mounted for movement adjacent the said receiver and operatively connected to the said breech-bolt for moving the same; a spring-pressed firing-member provided with a primary cocking-abutment, a secondary cocking-abutment and a tertiary cocking-abutment releasably engageable with the primary cocking-abutment of the said firing-member when the said trigger is released; a secondary sear having a secondary cocking-abutment normally releasably engageable with the secondary cocking-abutment of the said firing-member when the said trigger is pulled and movable with respect to the said trigger for being held in a retired position; a tertiary sear having a tertiary cocking-abutment releasably engageable with the tertiary cocking-abutment of the said firing-member; manually-operable control-means engageable with the said secondary sear for releasably holding the same in a retired position; means operatively connecting the said secondary sear to the said trigger to effect the movement of the former by the latter, the said means including a spring yieldingly urging the secondary cocking-abutment of the said secondary sear into position for releasable engagement with the secondary cocking-abutment of the said firing-member and permitting the relative movement of the secondary sear in the opposite direction; and means carried by the said bolt-operating member to retire the said tertiary sear as the said breech-bolt moves into its breech-closing position.

3. An automatic and semiautomatic firearm, including in combination: a receiver; a unit comprising a breech-bolt movable in the said receiver and a bolt-operating member mounted for movement adjacent the said receiver and operatively connected to the said breech-bolt for moving the same; a spring-pressed firing-member provided with a primary cocking-abutment, a secondary cocking-abutment and a tertiary cocking-abutment; a trigger; a primary sear operatively associated with the said trigger for being moved thereby and having a primary cocking-abutment

releasably engageable with the primary cocking-abutment of the said firing-member when the said trigger is released; a secondary sear having a secondary cocking-abutment normally releasably engageable with the secondary cocking-abutment of the said firing-member when the said trigger is pulled and movable with respect to the said trigger for being held in a retired position; a tertiary sear having a tripping-abutment and a tertiary cocking-abutment releasably engageable with the tertiary cocking-abutment of the said firing-member; manually-operable control-means engageable with the said secondary sear for releasably holding the same in a retired position; means operatively connecting the said secondary sear to the said trigger to effect the movement of the former by the latter, the said means including a spring yieldingly urging the secondary cocking-abutment of the said secondary sear into position for releasable engagement with the secondary cocking-abutment of the said firing-member and permitting the relative movement of the secondary sear in the opposite direction; and a tripping-abutment carried by the said unit and engageable with the tripping-abutment of the said tertiary sear as the said breech-bolt moves into its breech-closing position to retire the said tertiary sear.

4. An automatic and semiautomatic firearm, including in combination: a receiver; a breech-bolt movable in the said receiver; a bolt-operating member mounted for movement adjacent the said receiver and operatively connected to the said breech-bolt for moving the same; a spring-pressed firing-member provided with a primary cocking-abutment, a secondary cocking-abutment and a tertiary cocking-abutment; a trigger; a primary sear operatively associated with the said trigger for being moved thereby and having a primary cocking-abutment releasably engageable with the primary cocking-abutment of the said firing-member when the said trigger is released; a secondary sear having a secondary cocking-abutment normally releasably engageable with the secondary cocking-abutment of the said firing-member when the said trigger is pulled and movable with respect to the said trigger for being held in a retired position; a tertiary sear having a tripping-abutment and a tertiary cocking-abutment releasably engageable with the tertiary cocking-abutment of the said firing-member; manually-operable control-means engageable with the said secondary sear for releasably holding the same in a retired position; means operatively connecting the said secondary sear to the said trigger to effect the movement of the former by the latter, the said means including a spring yieldingly urging the secondary cocking-abutment of the said secondary sear into position for releasable engagement with the secondary cocking-abutment of the said firing-member and permitting the relative movement of the secondary sear in the opposite direction; and a tripping-abutment carried by the said bolt-operating member and engageable with the tripping-abutment of the said tertiary sear as the said breech-bolt moves into its breech-closing position to retire the said tertiary sear.

5. An automatic and semiautomatic firearm, including in combination: a receiver; a unit comprising a breech-bolt movable in the said receiver and a bolt-operating member mounted for movement adjacent the said receiver and operatively connected to the said breech-bolt for moving the same; a spring-pressed firing-member provided

with a primary cocking-abutment, a secondary cocking-abutment and a tertiary cocking-abutment; a trigger; a primary sear rigid with the said trigger for movement therewith and having a primary cocking-abutment releasably engageable with the primary cocking-abutment of the said firing-member when the said trigger is released; a secondary sear yieldingly carried by the said trigger and having a secondary cocking-abutment normally releasably engageable with the secondary cocking-abutment of the said firing-member when the said trigger is pulled and movable with respect to the said trigger for being held in a retired position; a tertiary sear having a tertiary cocking-abutment releasably engageable with the tertiary cocking-abutment of the said firing-member; manually-operable control-means engageable with the said secondary sear for releasably holding the same in a retired position; means operatively connecting the said secondary sear to the said trigger to effect the movement of the former by the latter, the said means including a spring yieldingly urging the secondary cocking-abutment of the said secondary sear into position for releasable engagement with the secondary cocking-abutment of the said firing-member and permitting the relative movement of the secondary sear in the opposite direction; and means actuated by the said unit to retire the said tertiary sear as the said breech-bolt moves into its breech-closing position.

6. An automatic and semiautomatic firearm, including in combination: a receiver; a breech-bolt movable in the said receiver; a bolt-operating member mounted for movement adjacent the said receiver and operatively connected to the said breech-bolt for moving the same; a spring-pressed firing-member provided with a primary cocking-abutment, a secondary cocking-abutment and a tertiary cocking-abutment; a trigger; a primary sear rigid with the said trigger for movement therewith and having a primary cocking-abutment releasably engageable with the primary cocking-abutment of the said firing-member when the said trigger is released; a secondary sear yieldingly carried by the said trigger and having a secondary cocking-abutment normally releasably engageable with the secondary cocking-abutment of the said firing-member when the said trigger is pulled and movable with respect to the said trigger for being held in a retired position; a tertiary sear having a tertiary cocking-abutment releasably engageable with the tertiary cocking-abutment of the said firing-member; manually-operable control-means engageable with the said secondary sear for releasably holding the same in a retired position; means operatively connecting the said secondary sear to the said trigger to effect the movement of the former by the latter, the said means including a spring yieldingly urging the secondary cocking-abutment of the said secondary sear into position for releasable engagement with the secondary cocking-abutment of the said firing-member and permitting the relative movement of the secondary sear in the opposite direction; and means carried by the said bolt-operating member to retire the said tertiary sear as the said breech-bolt moves into its breech-closing position.

7. An automatic and semiautomatic firearm, including in combination: a receiver; a unit comprising a breech-bolt movable in the said receiver and a bolt-operating member mounted for movement adjacent the said receiver and oper-

8. An automatic and semiautomatic firearm, including in combination: a receiver; a breech-bolt movable in the said receiver; a bolt-operating member mounted for movement adjacent the said receiver and operatively connected to the said breech-bolt for moving the same; a spring-pressed firing-member provided with a primary cocking-abutment, a secondary cocking-abutment and a tertiary cocking-abutment; a trigger; a primary sear rigid with the said trigger for movement therewith and having a primary cocking-abutment releasably engageable with the primary cocking-abutment of the said firing-member when the said trigger is released; a secondary sear yieldingly carried by the said trigger and having a secondary cocking-abutment normally releasably engageable with the secondary cocking-abutment of the said firing-member when the said trigger is pulled and movable with respect to the said trigger for being held in a retired position; a tertiary sear having a tripping-abutment and a tertiary cocking-abutment releasably engageable with the tertiary cocking-abutment of the said firing-member; manually-operable control-means engageable with the said secondary sear for releasably holding the same in a retired position; means operatively connecting the said secondary sear to the said trigger to effect the movement of the former by the latter, the said means including a spring yieldingly urging the secondary cocking-abutment of the said secondary sear into position for releasable engagement with the secondary cocking-abutment of the said firing-member and permitting the relative movement of the secondary sear in the opposite direction; and a tripping-abutment carried by the said bolt-operating member and engageable with the tripping-abutment of the said tertiary sear as the said breech-bolt moves into

its breech-closing position to retire the said tertiary sear.

9. An automatic and semiautomatic firearm, including in combination: a receiver; a unit comprising a breech-bolt movable in the said receiver and a reciprocating bolt-operating slide mounted for reciprocation adjacent the said receiver and operatively connected to the said breech-bolt for moving the same; a spring-pressed firing-member provided with a primary cocking-abutment, a secondary cocking-abutment and a tertiary cocking-abutment; a trigger; a primary sear operatively associated with the said trigger for being moved thereby and having a primary cocking-abutment releasably engageable with the primary cocking-abutment of the said firing-member when the said trigger is released; a pivotal secondary sear having a secondary cocking-abutment normally releasably engageable with the secondary cocking-abutment of the said firing-member when the said trigger is pulled and movable with respect to the said trigger for being held in a retired position; a reciprocating tertiary sear having a tertiary cocking-abutment releasably engageable with the tertiary cocking-abutment of the said firing-member; manually-operable control-means engageable with the said secondary sear for releasably holding the same in a retired position; means operatively connecting the said secondary sear to the said trigger to effect the movement of the former by the latter, the said means including a spring yieldingly urging the secondary cocking-abutment of the said secondary sear into position for releasable engagement with the secondary cocking-abutment of the said firing-member and permitting the relative movement of the secondary sear in the opposite direction; and means actuated by the said unit to retire the said tertiary sear as the said breech-bolt moves into its breech-closing position.

10. An automatic and semiautomatic firearm, including in combination: a receiver; a breech-bolt movable in the said receiver; a reciprocating bolt-operating slide mounted for reciprocation adjacent the said receiver and operatively connected to the said breech-bolt for moving the same; a spring-pressed firing-member provided with a primary cocking-abutment, a secondary cocking-abutment and a tertiary cocking-abutment; a trigger; a primary sear operatively associated with the said trigger for being moved thereby and having a primary cocking-abutment releasably engageable with the primary cocking-abutment of the said firing-member when the said trigger is released; a pivotal secondary sear having a secondary cocking-abutment normally releasably engageable with the secondary cocking-abutment of the said firing-member when the said trigger is pulled and movable with respect to the said trigger for being held in a retired position; a reciprocating tertiary sear having a tertiary cocking-abutment releasably engageable with the tertiary cocking-abutment of the said firing-member; manually-operable control-means engageable with the said secondary sear for releasably holding the same in a retired position; means operatively connecting the said secondary sear to the said trigger to effect the movement of the former by the latter, the said means including a spring yieldingly urging the secondary cocking-abutment of the said secondary sear into position for releasable engagement with the secondary cocking-abutment of the said firing-member and permitting the relative move-

ment of the secondary sear in the opposite direction; and means carried by the said bolt-operating slide to retire the said tertiary sear as the said breech-bolt moves into its breech-closing position.

11. An automatic and semiautomatic firearm, including in combination: a receiver; a unit comprising a breech-bolt movable in the said receiver and a reciprocating bolt-operating slide mounted for reciprocation adjacent the said receiver and operatively connected to the said breech-bolt for moving the same; a spring-pressed firing-member provided with a primary cocking-abutment, a secondary cocking-abutment and a tertiary cocking-abutment; a trigger; a primary sear rigid with the said trigger for movement therewith and having a primary cocking-abutment releasably engageable with the primary cocking-abutment of said firing-member when the said trigger is released; a pivotal secondary sear yieldingly carried by the said trigger and having a secondary cocking-abutment normally releasably engageable with the secondary cocking-abutment of the said firing-member when the said trigger is pulled and movable with respect to the said trigger for being held in a retired position; a reciprocating tertiary sear having a rearwardly-facing tripping-abutment and a tertiary cocking-abutment releasably engageable with the tertiary cocking-abutment of the said firing-member; manually-operable control-means engageable with the said secondary sear for releasably holding the same in a retired position; means operatively connecting the said secondary sear to the said trigger to effect the movement of the former by the latter, the said means including a spring yieldingly urging the secondary cocking-abutment of the said secondary sear into position for releasable engagement with the secondary cocking-abutment of the said firing-member and permitting the relative movement of the secondary sear in the opposite direction; and a forwardly-facing tripping-abutment carried by the said unit and engageable with the rearwardly-facing tripping-abutment of the said tertiary sear as the said breech-bolt moves into its breech-closing position to retire the said tertiary sear.

12. An automatic and semiautomatic firearm, including in combination: a receiver; a breech-bolt movable in the said receiver; a reciprocating bolt-operating slide mounted for reciprocation adjacent the said receiver and operatively connected to the said breech-bolt for moving the same; a spring-pressed firing-member provided with a primary cocking-abutment, a secondary cocking-abutment and a tertiary cocking-abutment; a trigger; a primary sear rigid with the said trigger for movement therewith and having a primary cocking-abutment releasably engageable with the primary cocking-abutment of the said firing-member when the said trigger is released; a pivotal secondary sear yieldingly carried by the said trigger and having a secondary cocking-abutment normally releasably engageable with the secondary cocking-abutment of the said firing-member when the said trigger is pulled and movable with respect to the said trigger for being held in a retired position; a reciprocating tertiary sear having a rearwardly-facing tripping-abutment and a tertiary cocking-abutment releasably engageable with the tertiary cocking-abutment of the said firing-member; manually-operable control-means engageable with the said secondary sear for releasably holding the same in a retired position; means operatively connecting the said secondary sear to the said trigger to effect the movement of the former by the latter, the said means including a spring yieldingly urging the secondary cocking-abutment of the said secondary sear into position for releasable engagement with the secondary cocking-abutment of the said firing-member and permitting the relative movement of the secondary sear in the opposite direction; and a forwardly-facing tripping-abutment carried by the said bolt-operating slide and engageable with the rearwardly-facing tripping-abutment of the said tertiary sear as the said breech-bolt moves into its breech-closing position to retire the said tertiary sear.
